UNITED STATES PATENT OFFICE.

TAYLOR HOYT MACLAFFERTY, OF TENINO, WASHINGTON.

CAR-STAKE.

No. 928,203.

Specification of Letters Patent. Patented June 29, 1909.

Application filed January 5, 1909. Serial No. 470,813.

To all whom it may concern:

Be it known that I, TAYLOR H. MACLAFFERTY, a citizen of the United States, residing at Tenino, in the county of Thurston and State of Washington, have invented a new and useful Car-Stake, of which the following is a specification.

This invention relates to improvements in detachable devices for retaining and releasing logs upon railway cars or trucks; and has for one of its objects the provision of an improved means for reliably accomplishing this result, and at the same time affording means whereby the logs may be conveniently released without endangering the safety of the operator.

A further object is to provide a device which can be readily attached to most forms of car bunks now in use.

A still further object is to provide a means which will, when released, effect the dislodgment of the logs without danger of binding.

With these and other objects in view, as will more fully hereinafter appear, the present invention consists in certain novel details of construction and arrangement of parts, hereinafter fully described, illustrated in the accompanying drawings, and more particularly pointed out in the appended claims, it being understood that various changes in the form, proportion, size and minor details of the device may be made without departing from the spirit or sacrificing any of the advantages of the invention.

In the accompanying drawings:—Figure 1 is a front elevation of a car bunk equipped with my device. Fig. 2 is an end view of the same. Fig. 3 is a detail front elevation, showing the device in releasing position. Fig. 4 is a detail perspective of the chock.

Similar numerals of reference are employed to designate corresponding parts throughout.

In carrying out my invention I arrange within the channel of the bunk a suitable chock, one side of which is pivoted to the bunk and the opposite side adapted to bear on the outer end of the bunk. The normal position of the parts just described is such that the upper end of the chock will be substantially vertical and above the plane of the bunk. When in this position logs may be piled upon the bunk in the usual manner and prevented from falling by the chock. The latter is held in its upright position by

means of a suitable keeper, one end of which is connected to one face of the bunk, and the intermediate portion of which bears on one side of the chock. A connection is established between the free end of the keeper and the opposite face of the bunk, and this connection is such that it may, by means of suitable mechanism, be released, and thus free the keeper of its bearing position on the chock, whereby the latter will fall within the bunk and permit the dislodgment of the logs.

It is a well known fact that considerable difficulty is experienced with devices of this kind in dislodging logs; this is due chiefly to the fact that the parts are so constructed that the weight of the logs causes the chock to bind against the bunk, so that when the means for holding the latter in upright position is released, the chock fails to respond to the usual outward movement, consequently, it is necessary to pry or start the logs with a suitable implement, or else force the chock outward. This procedure has many disadvantages, chief among which is that the operator is compelled to approach that side of the bunk from which the logs are to be discharged and it frequently happens that the movement of the pile starts at an unexpected moment, whereby considerable injury is often inflicted upon the attendant. The present invention aims to remedy this defect by so constructing the chock that the danger of binding will be reduced to a minimum.

The chock consists of two legs of suitable lengths, one of which is pivoted, as at 1 by a transversely disposed bolt arranged in the bunk 2. The latter is of a well known construction having its upper face channeled. The chock is disposed adjacent either end of the bunk and is so positioned that it will fall within the channel when released. As before stated, one leg of the chock has one end pivoted within the channel of the bunk, and the opposite leg 3 is provided at one end with a substantially right angular offset 4. This offset is adapted to straddle the upper edge at one end of the bunk, as clearly shown in Figs. 1 and 2. It will be observed that the offset 4 is not truly right angular. That portion projecting laterally from the end of the leg 3 lies at an obtuse angle to the leg, while the depending extension is bent downwardly and substantially parallel with the leg 3. From what will subsequently appear, it can be seen that this construction is designed to

give better results than if the offset were truly right angular. The opposite end of the leg 3 terminates in an eye or opening 5, while that end of the opposite leg 6 of the chock 5 remote from the pivoted end is reduced so as to form a neck 7; this neck is curved outwardly and inwardly and extends through the opening 5 of the leg 3, and at its extremity is provided with an enlarged circular head 8 of greater diameter than the opening 5. Thus it can be seen when the parts are connected in this position and as shown in Figs. 1 to 4 inclusive, the legs will be permanently combined together, it being understood that 10 the diameter of the neck 7 is considerably less than that of the opening 5, in order to permit a relative lateral movement between the legs. As before stated, the terminal of the leg 6 is pivoted within the channel of the 15 bunk at a point adjacent one end thereof, and is so positioned that when it falls outwardly and within the channel, the head 8 will fall on the upper and outer edge of the bunk, as shown in Fig. 3. When in operative 20 position, the leg 6 is brought upright, and this upright movement of the arm will carry with it the leg 3. The offset of the latter is now positioned to straddle the upper and outer edge of the bunk, as shown in Figs. 25 1 and 2. Owing to the length of the leg 3, the leg 6 will be inclined outwardly when the offset engages the end of the bunk, as before described. In order to secure the parts in this position, the following device is employed:

By referring now to Figs. 1 to 3 inclusive it will be seen that the end of the bunk is provided with an inwardly extending and horizontally disposed recess or seat 9. This recess is disposed above the floor of the channel and adjacent the upper face of the bunk, and is designed to hold a suitable bar or bolt 10. The length of the latter is considerably greater than the width of the bunk and when seated within the recess or seat 9, its opposite ends will project beyond the outer faces of the bunk. Each end of the bar 10 terminates in an eye or opening 11, and secured to one face of the bunk is an eye bolt 12. Connection 40 between the latter and one end of the bolt 10 is established by means of a chain or other flexible element 13. Anchored in that face of the bunk opposite the eye bolt 12 is a similar eye bolt 14 which supports a hook. The shank 15 of the latter terminates at one end in an eye which engages the eye bolt 14, and at its opposite end has a similar eye. The bill 16 of the said hook is preferably right angular in shape having arms of unequal length. The shorter of these arms is provided with an eye, which engages the eye at the free end of the shank 15, the said short arm terminating in an enlarged circular head 17, which, as before stated, is provided with an eye for the reception of the

shank 15. Owing to this construction a socket is formed by the circular head 17 and inner end of the long arm 16, the size of said socket being sufficient to snugly seat the end link of a length of chain 18, the opposite terminal of which is secured to that eye of the bar 10 remote from the chain 13. It will be understood that the long arm 16 of the hook is of a size to fit slidingly within the end link of the said chain 18. After the long arm 16 of the hook has been inserted into the end link of the chain 18, the said long arm may be turned parallel with the shank 15, such movement forcing the link into the socket. It is to be understood that the lengths of the chains 13 and 18 are such that, when the chain 18 is in engagement with the socket as hereinbefore described, the element 10, by means of said chains 13 and 18, will be held securely within the recess 9. It is obvious that in order to maintain the parts in this position, a clamp or similar device must be employed to encircle the hook and shank, and in order to effect this purpose, the following mechanism is employed, which is designed to 50 clamp the parts together, as already stated, and further designed to be operated to release the said parts from the remote end of the bunk, or in other words, the operator may dislodge the logs from the bunk by standing 55 on that side of the latter opposite the side over which the logs will fall.

By referring now to Figs. 1 and 3, it will be seen that on that face of the bunk to which is secured the forward hook, there is provided one or more eye bolts or guides 19, lying in a plane with the eye bolt 14, or substantially so. These eye bolts receive an operating rod 20, one end of which terminates in a handle 21 which lies adjacent that end of the bunk 100 remote from the chock, while the opposite end of the rod terminates in an upwardly extending arm 21. The latter is provided with an eye or opening 22 which completely encircles the shank 15 of the hook. Owing to the mounting of the rod 20, it can be seen that it may be reciprocated longitudinally with respect to the bunk, so that the eye portion will slide over the shank 15. Thus when it is moved so as to bring the eye 22 to the inner or connected end of the shank, the hook may be turned so as to bring the long arm 16 parallel with the shank, as before described. When the parts are in this position, the rod is moved in an opposite direction which will result in the eye 22 sliding over the long arm 17 and shank 15. In this position, the parts are locked and when the chain 18 has been connected with the hook, as before described, and the chock adjusted to an upright position, the latter will perform its function of retaining the logs in the bunk. When the rod 20 is moved to releasing position and the eye bolt 14 brought from engagement with the long arm 16, the weight of the logs on the leg 6 of 131

the chock will cause the latter to move outwardly and downwardly, whereby a similar movement will be imparted to the leg 3. The latter, owing to the peculiar shape of the offset, before described, will offer little or no resistance to outward movement. Consequently, as the said arm 3 moves outward and downward, the bar 10 will also be moved from the socket 9 carrying with it the chains 10 13 and 18. The latter of these chains will rock the long arm of the hook outwardly, whereby the said chain will be freed.

From the foregoing, it will be seen that I have provided a device, which is simple in 15 structure, inexpensive to manufacture, and which may be readily applied to most forms of bunks now in use.

What is claimed is:—

1. A chock formed of two legs one of which 20 is provided with an opening adjacent one end, and the other having a curved end portion to loosely fit within said opening.

2. A chock formed of two legs one of which is provided with an opening adjacent one 25 end, and the other having a downwardly and upwardly curved end portion to loosely fit within said opening.

3. A chock formed of two legs one of which is provided with an opening adjacent one 30 end, and the other having a reduced neck portion to enter said opening.

4. A chock formed of two legs one of which is provided with an opening adjacent one end, and the other having a reduced neck 35 portion to enter said opening, the said reduced neck portion terminating in an enlarged head constituting a means for locking the legs together.

5. A chock formed of two legs one of which 40 is provided at one end with an angular offset,

and having at its opposite end an opening, and the other of said legs having a reduced neck portion loosely fitted within said opening, said neck portion terminating in a flattened head constituting a means for locking 45 the legs together.

6. The combination with a bunk, of a chock having two legs one of which is pivoted to said bunk and the other having an offset 50 to bear on the end of said bunk.

7. The combination with a bunk, of a chock having a pair of interlocking legs one of which is pivoted to said bunk, and the other having at one end an angular offset to bear on the end of said bunk. 55

8. The combination with a bunk, of a chock having a pair of interlocking arms, one of which is pivoted to said bunk, the other of said arms having an angular offset to straddle the edge of said bunk, and a releasable 60 means for securing the angular offset against outward movement from said bunk. 60

9. A device of the class described comprising a bunk; a hook pivoted at one end to the bunk and terminating in a pivoted arm; an operating rod mounted upon the bunk, and terminally provided with a rigid eye arranged to inclose the hook, the rod being slidable to cause the eye to engage the extremity of the arm of the hook; a chock; and means engageable by the arm of the hook for holding the chock assembled with the bunk. 65

In testimony that I claim the foregoing as my own, I have hereto affixed my signature in the presence of two witnesses.
